Samuel E. Adler, Chicago, Ill., assignor to Admiral Corporation, Chicago, Ill., a corporation of Delaware

Application January 25, 1954, Serial No. 28,647

Term of patent 14 years

(Cl. D56—4)

To all whom it may concern:

Be it known that I, Samuel E. Adler, a citizen of the United States, residing at Chicago, in the county of Cook, State of Illinois, have invented a new, original, and ornamental Design for a Television Cabinet, of which the following is a specification, reference being had to the accompanying drawings, forming a part hereof.

Fig. 1 is a perspective view of a television cabinet, showing my new design; and

Fig. 2 is a fragmentary side elevational view thereof, the front being broken away to reveal the formation of the front of the cabinet.

I claim:

The ornamental design for a television cabinet, as shown.
